(57) **CLAIM**

The ornamental design for a combination alarm tag as shown and described.

DESCRIPTION

FIG. 1 is a front upper perspective view of a combination alarm tag of our new design;

FIG. 2 is a rear upper perspective view thereof;

FIG. 3 is a front view thereof;

FIG. 4 is a rear view thereof.

FIG. 5 is a right side view thereof.

FIG. 6 is a left side view thereof.

FIG. 7 is a top view thereof; and,

FIG. 8 is a bottom view thereof.

The broken lines depict portions of the article and environment that form no part of the claimed design.

1 Claim, 6 Drawing Sheets
